TOY OIL WELL PUMP

Kenneth B. Cope, Bradford, Pa.

Application May 5, 1955, Serial No. 35,819

Term of patent 14 years

(Cl. D34—15)

FIG. 1

FIG. 2

FIG. 3

Fig. 1 is a top plan view of a toy oil well pump, showing my new design;

Fig. 2 is a side elevational view thereof; and

Fig. 3 is an end elevational view thereof.

I claim:

The ornamental design for a toy oil well pump, as shown.
